UNITED STATES PATENT OFFICE.

WILLY JAEGER, OF PROVIDENCE, RHODE ISLAND, ASSIGNOR TO SPEIDEL CHAIN CO., OF PROVIDENCE, RHODE ISLAND, A FIRM COMPOSED OF FREDERICK SPEIDEL AND ENGEN SPEIDEL, BOTH OF PFORZHEIM, GERMANY.

CHAIN LINK.

Application filed April 29, 1925, Serial No. 26,658.

This invention relates to an improved construction of links for ornamental chains for personal wear; and has for its object to provide simple and effective means for applying 5 ornamentation to the links of the chain.

A further object of this invention is the provision of a link of the elongated loop form having means on its inner surface for receiving and retaining ornamentation 10 therein.

With these and other objects in view, the invention consists of certain novel features of construction, as will be more fully described, and particularly pointed out in the 15 appended claims.

In the accompanying drawings:

Figure 1 is a side elevation showing a plurality of my improved ornamental links as connected together to form a chain.

Figure 2 is a perspective view of a strip of sheet stock from which my improved form of link is cut or stamped.

Figure 3 is a perspective view showing one of the links as cut from the sheet stock.

Figure 4 is a perspective view showing one of the many forms of ornamental members which is adapted to be mounted in the elongated link.

Figure 5 shows another form of such ornamental member.

Figure 6 is an edge elevation illustrating one of these ornamental members as mounted in the link.

Figure 7 is a sectional edge view on line 35 7-7 of Figure 6, showing the ornamentation in the openings or notches in the link.

Figure 8 is a perspective view showing one form of ornamentation as mounted in my improved form of elongated link.

It is found in the practical construction 40 of ornamental chains for personal wear, of advantage to blank some of the links from sheet stock to form a seamless loop, preferably with an open center portion, the inner

45 edges of the side arms of the link being notched or transversely grooved adjacent the ends thereof for the reception of ornaments of band shape and other shapes, many forms of which may be employed and

50 mounted in these different links to provide ornamental links of widely varying types and designs. One advantage of such ornamental link is that the ornamental member

may be treated and finished independently and in a color or shade different from that 55 of the main link and subsequently connected to this link without the use of solder.

It is also found that by deeply notching or grooving the inner surfaces of these elongated links that the edges of the bands may 60 be securely mounted therein and after having been positioned the sides of the links may be closed or pressed inwardly causing 65 inwardly-projecting portions thereof to abut thereby forming stops to facilitate the assembling of the link parts; and the following is a detailed description of the present embodiment of my invention and showing 70 one construction of link by which these advantageous results may be accomplished:—

With reference to the drawings, 10 designates the elongated link which is preferably cut or struck from the sheet stock 11 to form a seamless elongated loop in which the side arms 12 are formed wider than the end portions 13 of the link. Laterally cut notches 14 are formed adjacent the ends of the loop for the reception of the connecting links 15 of the chain and laterally-cut notches 17 are spaced from the notches 14 for the reception 80 of the ends of the ornamental band members 18, presently described.

Between these notches 14 and 17 are oppositely-disposed inwardly-extending fingers 16 which are of a length a little greater 85 than the width of the side arms 12 so that when these side arms are pressed inwardly into the shape, as best illustrated in Figure 7, the ends of these fingers 16 are caused to abut and the lateral notches 14 form a substantially-circular opening 19 at the ends of the link, while the notches 17 are caused to closely embrace the band 18 mounted therein to bind the same firmly into position against 90 any endwise movement.

Different types of these ornamental bands such as illustrated in Figures 4 and 5, may be of different desired shapes, sizes, and colors and arranged to be mounted in the elongated loop links and firmly retained 100 therein by simply forcing together the side arms of the link.

My improved form of chain link is very simple and practical in construction and by the insertion of the ornamental member 105 which may be finished a color different from

that of the top of the main link, the chain formed thereof is rendered very handsome and attractive.

The foregoing description is directed solely towards the construction illustrated, but I desire it to be understood that I reserve the privilege of resorting to all the mechanical changes to which the device is susceptible, the invention being defined and limited 10 only by the terms of the appended claims.

I claim:

1. In a chain, an elongated seamless loop link formed of sheet stock with recesses in the inner surfaces of its side arms and an 15 ornamented loop having its end portions mounted in said recesses.

2. A chain link of elongated form having side arms with parallel edges, the inner sur-

faces of said arms being notched, an ornamental member having portions in said 20 notches and inwardly-projecting abutting extensions on said arms adjacent said notches.

3. A chain link comprising an outer loop portion with internal projections extending 25 toward each other from the side arms thereof and having recesses in said arms adjacent said projections, an ornamental inner band loop having its end portions mounted in said recesses, the arms of said outer loop being bent inwardly to cause said projections to abut and to lock said ornamental loop in its assembled position.

In testimony whereof I affix my signature.

WILLY JAEGER.
